CUSHIONING MECHANISM

Donald S. Barrows, Rochester, N. Y., assignor to
 The Symington Company, New York, N. Y., a
 corporation of Maryland

Application December 23, 1929, Serial No. 416,113

17 Claims. (Cl. 213—22)

This invention relates to draft rigging, and more particularly to spring and friction draft gears especially adapted for use on railway vehicles.

5 The principal object of my invention, generally considered, is to provide friction draft gears or cushioning mechanism especially adapted for railway service and having housings or casings so slotted that they are adapted to receive draft 10 keys for connection with associated sills whereby, if desired, the inner ends of said gears only may be employed for cushioning draft forces and both ends may be used for cushioning buffing forces.

15 Another object of my invention is to provide cushioning mechanism comprising an enclosing housing or casing, preferably open at both ends, and formed with inclined friction surfaces at said ends, the angularity of the friction surfaces 20 at one end being normal and that at the other end being greater than normal so as to provide for self-releasing of the associated wedges, the wedges at the first-mentioned end being provided with an intermediate follower and release 25 springs, some of said release springs continuing toward the other end of the gear to engage a corresponding follower for the other wedges to hold said follower thereagainst and avoid the necessity of nibs on the wedge springs and 30 pockets in the wedges for holding said springs in place.

A further object of my invention is to provide friction wedges for use with cushioning mechanism or draft gears and formed with spring retaining lugs on the inner ends and/or with shoe castings interlocking therewith to decrease the abrasive action of the wedges on the associated follower by increasing the engaging areas and 40 retaining the associated wedge springs in proper position.

A still further object of my invention is the provision of friction wedges for railway draft gears or cushioning mechanism each involving a special main wedge and shoe interlocked therewith and providing flanges overlying the ends of the associated curved plate springs for holding them in position and preventing them from gouging the associated follower, said flanges increasing the area engaged by said follower for 45 decreasing wear therebetween.

An additional object of my invention is to provide friction wedges for use with railway draft gears and adapted to receive interior or intermediate follower plates in rectangular slots or notches in the tails thereof, said follower plates

being thereby adapted to retain associated curved plate springs in place.

Other objects and advantages of the invention relating to the particular arrangement and construction of the various parts will become 5 apparent as the description proceeds.

Referring to the drawings illustrating my invention, the scope whereof is defined by the appended claims:—

Figure 1 is a partial side elevation and partial 10 vertical longitudinal sectional view of a form of draft gear or cushioning mechanism embodying my invention, the associated front and rear or outer followers being diagrammatically illustrated.

Fig. 2 is a partial end elevation and partial transverse sectional view on the line 2—2 of Fig. 1 looking in the direction of the arrows.

Fig. 3 is a fragmentary partial side elevation and partial vertical longitudinal sectional view 20 of another embodiment of my invention.

Fig. 4 is a partial side elevation and partial vertical longitudinal sectional view of a further embodiment of my invention, the associated coupler, yoke, front and rear followers and connecting key being diagrammatically illustrated.

Fig. 5 is a partial plan and partial horizontal sectional view of the embodiment of my invention illustrated in Fig. 4.

Figs. 6, 7, 8 and 9 are transverse sectional views 30 on correspondingly numbered lines of Fig. 4 looking in the directions of the arrows.

Fig. 10 is a rear end elevation of the mechanism shown in Fig. 4 with the rear follower removed.

Fig. 11 is a front end elevation of the mechanism shown in Fig. 4 with the front follower removed.

Fig. 12 is a side elevation of one of the wedge shoes, for the front or outer friction wedges, removed from the gear.

Fig. 13 is an end elevation of said wedge shoe.

Fig. 14 is a side elevation shown partially in vertical section of one of the wedge shoes, of inner or rear friction wedges, removed from the 45 gear.

Referring to the drawings in detail, like parts being designated by like reference characters, and first considering the embodiment of my invention illustrated in Figs. 1 and 2, there is shown a 50 double-ended series friction draft gear or cushioning mechanism particularly adapted for use on railway vehicles and preferably designed so that it will fit into a draft gear pocket of normal size. In the embodiment shown, it is of a length 55

corresponding with that of a standard size draft gear pocket allowing for the increased coupler travel provided.

The gear preferably comprises a spring barrel or housing 2 with its ends open and formed with outwardly flaring walls 3 providing inclined friction surfaces 4. Received between said walls 3 are wedges or wedge blocks 5 having correspondingly inclined friction surfaces 6 normally engaging the friction surfaces 4 on the housing or casing 2. In order to interlock the wedge blocks 5 with the housing, the same are preferably formed with inner shouldered portions 7 which engage correspondingly shouldered portions 8 at the inner ends of the inclined surfaces 4 on the housing, thereby preventing undesired withdrawal of said wedge blocks. Disposed between the wedge blocks 5, for urging them apart and into engagement with the inclined friction surfaces on the housing, are two sets of curved plate or leaf springs 9, each set of which has its concave side preferably disposed toward the corresponding wedge block so that the ends 10 thereof engage said wedge blocks and urge them into frictional engagement with the inclined portions of the housing, while the convex sides of the spring sets engage one another without danger of slipping out of proper contact.

The inner ends of the wedge blocks are engaged by intermediate followers 11 which are, in turn, engaged by release springs 12 preferably comprising two pairs of spring units, each unit comprising outer coils 13 and inner coils 14. The inner ends of said release springs preferably engage fixed portions of the housing 2 such as the transverse partition or wall 15. Although only one end of the gear is shown in section, it will be understood that the interior construction of the other end may be identical, as in the embodiment under consideration, or different, as will be described in connection with a succeeding embodiment.

In order to provide for connection of the gear with associated sills so that, if desired, only the rearmost or inner mechanism is stressed under the action of draft forces and all of the mechanism is stressed under the action of buffing forces, as will be more fully explained in connection with a succeeding embodiment of my invention, the housing 2 is preferably formed with a horizontal slot 16 disposed in a portion 17 of the housing extending forwardly and rearwardly from the partition 15 and forming, in effect, a partition dividing the housing into upper and lower compartments and extending transversely between the side walls thereof, said extensions preferably lying between the upper and lower pairs of spring units 12. The gear 1 may be used with front and rear followers 18 and 19 diagrammatically illustrated, the front follower 18, as will be understood, being normally engaged by the butt of an associated coupler (not shown), and the rear follower normally surrounded by a yoke (not shown) which, in turn, engages an associated back stop (not shown).

Referring now to the embodiment of my invention illustrated in Fig. 3, a form of single-ended draft gear is there disclosed which is similar in most respects to the form of double-ended draft gear illustrated in Figs. 1 and 2. The gear 1^a shown in Fig. 3 comprises a housing or casing 2^a open at one end and closed by a wall 15^a at the other end. The open end, as in the previous embodiment, is provided with inwardly converging walls 3^a, which walls, however, are, in the pres-

ent embodiment, shown as formed on separable shoes 20 having lugs or flanges 21 and 22 fitting in corresponding pockets 23 and 24 in the adjacent walls of the housing 2^a. The sloping portions 3^a of the shoes 20 provide inclined friction surfaces 4^a adapted to be engaged by corresponding surfaces 6^a on wedge blocks 5^a. In order to interlock the wedge blocks 5^a with respect to the housing 2^a, the same are preferably formed with inner shouldered portions 7^a overlying the inner ends of the shoes 20, thereby preventing undesired withdrawal of the wedge blocks. Disposed between said wedge blocks 5^a for urging them apart and into engagement with the inclined friction surfaces 4^a are two sets of curved plate or leaf springs 9^a, as in the previous embodiment.

The inner ends of the wedge blocks 5^a preferably engage an inner or intermediate follower 11^a which is, in turn, engaged by release springs 12^a. Between said release springs, as in the previous 20 embodiment, is an extension 17^a from the wall 15^a slotted as at 16^a for receiving a connecting draft key (not shown). The upper and lower walls 25 of the housing may be curved around the release springs, in a manner corresponding to that shown 25 in Fig. 2, to assist in properly guiding them, and in order to maintain the proper relation between the intermediate follower 11^a and said springs, said follower is provided with spring-positioning lugs 26 engaging the adjacent ends of the release 30 springs 12^a. It will be understood that the gear of the present embodiment is adapted to interchange with ordinary forms of single or single-ended gears and not with double-ended gears, such as illustrated in the first embodiment. 35

Referring now to the embodiment of my invention illustrated in Figs. 4 to 14, inclusive, there is shown a slotted double-ended series friction draft gear as in the embodiment of Figs. 1 and 2, but of different construction, that is, with a front or outer end formed differently from the rear or inner end on account of the difference in use accorded the two ends of the gear. The gear 1^b is mounted between sills (not shown) and is normally associated with a coupler 27, diagrammatically illustrated, the butt of which is normally in engagement with the front follower 18^b. A yoke 28, diagrammatically illustrated, normally surrounds the gear with the closed or looped end thereof in engagement with the rear follower 19^b. As in the first embodiment, the housing 2^b of the gear is provided with a slot 16^b receiving a connecting draft key 29 which is adapted to not only pass through said slot, but through registering slots 30 in the yoke and associated cheek plates 55 and/or draft sills (not shown). The slots 30 in the yoke and cheek plates and/or sills are rearwardly elongated, as particularly illustrated in Fig. 4 for a purpose to be more fully explained hereinafter. 60

The gear 1^b comprises a housing or casing 2^b open at each end which is formed bell-mouthing or provided with sloping walls 3^b, the inner surfaces of which provide inclined friction faces 4^b normally engaged by corresponding surfaces 6^b on wedge blocks 5^b. As in the previous embodiment, the wedge blocks 5^b have shouldered portions 7^b engaging correspondingly shouldered portions 8^b on the housing to limit outward movement of said wedge blocks. The wedge blocks at opposite ends 70 of the gear are of different construction, as will be apparent from a consideration of Fig. 4, and will now be described in detail.

The friction blocks 5^b at the inner or rear end of the gear 1^b and the correspondingly inclined fric- 75

tion surfaces on the housing are disposed at an angle corresponding with that of the inclined friction surfaces of the embodiments of Figs. 1, 2 and 3 so that the blocks are not self-releasing and are, therefore, necessarily used with release springs. On the other hand, the blocks 5^b at the outer or front end of the gear and the inclined walls of the housing have friction surfaces inclined at a steeper angle so that the blocks are self-releasing and do not necessitate the use of release springs for that purpose. On account of this construction, the inner blocks 5^b have an inner intermediate follower 11^b engaging the inner ends of said wedge blocks 5^b and preferably fitting in notches 31 therein, the opposite face of said follower being engaged by two sets of helical leaf spring units 12^b, each set, as in the first embodiment, preferably comprising an outer spring 13^b and an inner spring 14^b. The inner or opposite end 20 of the outer spring 14^b normally engages a transverse web, wall or flange 15^b on the housing 2^b which flange is preferably apertured, as indicated at 32, to permit passage of the inner spring 14^b, which inner spring preferably extends into engagement with the outer or front intermediate follower 11^b, not primarily for the purpose of effecting release of the outer wedges 5^b but to hold the follower in place against the ends of the corresponding wedges and thereby avoid the necessity of special means such as nibs on the springs 9^b and corresponding pockets in the wedges 5^b for maintaining said springs in proper position with respect thereto. As in the embodiment of Fig. 3, the inner or rear intermediate follower 11^b 35 has spring retaining bosses 26^b.

In order to retain the springs 9^b in place and avoid gouging of the rear follower 19^b by said springs and the corresponding ends of the wedges 5^b, said wedges are preferably provided with shoes 40 or supplemental portions 33, the outer portions of which form flanges 34 overlying the ends of the shoes and extended beyond the springs 9^b, as indicated at 35, said extensions or lugs 35, however, being desirably formed to interfit one with the other, as shown particularly in Fig. 10, and thereby permit the closure of the gear. Each shoe 33 is formed with an inwardly extending flange 36 preferably provided with a conical or tapered lug 37 adapted to fit in a corresponding pocket 38 in the associated wedge block 5^b whereby when the springs 9^b are in place, the shoe 33 and associated wedge block 5^b are securely held in interlocked relation. The rear follower 19^b is desirably cut out or notched, as indicated at 39, to receive the shoes 33 without increasing the overall length of the gear.

In assembling the springs 9^b with the wedges 5^b and shoes 33, a flat piece of steel may first be inserted in the notched portion 40 in each wedge 60 which receives the flange 36 of the shoe 33 with its top flush with the top or inner surface of the wedge. The springs may then be assembled in the usual manner, and upon removal of the piece of steel, the wedge shoes may be driven into the spaces occupied thereby until the lugs 37 thereof interlock in the pockets 38, as shown most clearly in Fig. 4.

The wedges 5^b at the outer or front end of the gear may likewise be of special construction and 70 provided with wedge shoes or supplemental wedge portions 41 fitting in corresponding depressions or pockets 42 in the wedges 5^b, said shoes being preferably provided with inclined or sloping wall portions 43 notched or shouldered, as indicated at 75 44, to receive a corresponding projection or lug

45 on the corresponding wedge 5^b whereby each shoe may be assembled with its corresponding wedge by being forced into place between the wedge and the associated springs 9^b until the lug 45 snaps into interlocking position in the corresponding notch or pocket 44. The shoes 41 are provided with outer flanges or lugs 46 which overlie the outer ends of the springs 9^b and thereby hold them in position and prevent them from gouging the associated follower 18^b, at the same time increasing the wearing area in engagement with said follower and reducing wear on said follower. In order to permit compression of the gear, the flanges 46 are desirably inclined, as shown in Fig. 11, so as to avoid interference there- 15 between while at the same time providing sufficient height to retain the springs 9^b in place. The associated follower 18^b is preferably notched to receive the flanges 46 of the shoes 41 to thereby avoid increasing the overall length of the gear. 20 All the wearing surfaces on the wedges may, if desired, be provided with lead inserts 47 to prevent sticking and provide smoothness of operation, and the inner ends of all the wedges may have spring retaining lugs 48 which act as means 25 additional to the intermediate followers to hold the springs 9^b in place.

The operation of the gear of the present embodiment as well as that of the embodiment of Figs. 1 and 2 may be as follows, although it will 30 be understood that, if desired, the gear may be utilized as an ordinary single-ended gear so that the entire capacity is brought into action under both draft and buffering forces. When draft force is applied to the coupler 27, said force is transmitted from said coupler to the yoke 28 through the connecting key 49, thereby effecting a compression of the rearmost mechanism of the gear by forward movement of the rear follower 19^b forcing the rear wedges 5^b into the housing 2^b, 40 compressing the rear curved plate springs 9^b and the release springs 12^b, it being understood that the housing 2^b is prevented from forward movement by the connecting draft key 29 which passes through the slot 16^b in the housing and corresponding slots in the cheek plates and/or draft sills of the car.

Under the action of buffering force, however, the coupler 27 engages the front follower 18^b and pushes the front friction elements 5^b into the 50 housing 2^b simultaneously moving said housing rearwardly over the rear friction elements 5^b, which rearward movement is permitted on account of the rearward elongation of the slots 30 in the yoke and cheek plates of the car, it being 55 understood that the rear follower 19^b is held from rearward movement by means of a usual form of back stop (not shown). It will, therefore, be seen that full compression of the gear is permitted under the action of buffering force not only providing for increased buffering capacity, but for a coupler travel equal to the sum of the travel permitted by the friction elements at each end of the gear. Although, for convenience, the gear is preferably made so that the travel provided by each 65 end is identical yet this is not essential in accordance with the broad aspect of my invention as the travel may be different at each end of the gear and the capacity of each end may be the same as in accordance with the embodiment of my invention illustrated in Figs. 1 and 2, or different in accordance with the embodiment illustrated in Figs. 4 to 14, inclusive.

It will be seen that on account of the steeper angle of the wedges at the front end of the gear, 75

the front springs 9^b may be stressed to a greater extent, for a given wedge movement, than the rear springs 9^b so that if the springs at the two ends are of equal strength, a greater capacity is provided by the front portion of the gear than the rear portion. However, this capacity is modified by the fact that the release spring action provided for the rear wedges is greater than that provided for the front wedges so that the relative capacities of the two ends of the gear may be adjusted within wide limits. The wedges with the greater release spring capacity are desirably disposed at the rear or inner end of the gear as these wedges are always brought into play under both draft and buffing forces, whereas the front wedges are only used under the action of buffing forces when the gear is employed with draft rigging, as diagrammatically shown in Fig. 4. In this way, there is the certainty of having the usual release spring action for restoring the gear to normal after either draft or buffing action, restoration of the front portion of the gear being more readily effected when the gear has been partly released through the positive action of the rear release springs.

In accordance with the foregoing disclosure, it will be seen that I have devised a form of cushioning mechanism which involves a housing slotted for receiving a connecting draft key and which may be single-ended to interchange with the usual forms of single draft gears, all of which may be double-ended for series use giving, if desired, a differential capacity greater under the action of buffing forces than under the action of draft forces, it being well understood that buffing forces are always apt to be greater than draft forces. In accordance with my invention, I have also provided for either doubling the capacity and travel of the gear for absorbing buffing forces as compared with draft forces or for increasing such capacity and/or travel to the extent desired.

Although I have illustrated several preferred embodiments of my invention, it will be understood that modifications may be made within the spirit and scope of the appended claims.

I claim:

1. Cushioning mechanism adapted for use with railway draft rigging comprising a housing slotted adjacent an intermediate portion thereof for receiving a connecting draft key and open at each end, said open ends having the walls formed with inwardly converging friction surfaces, the surfaces at one end converging at a sharper angle than those at the other end, wedges having correspondingly inclined friction surfaces engaging the friction surfaces of the housing and movable thereinto, curved leaf springs disposed between said wedges for urging them apart and into engagement with the friction surfaces on the housing, intermediate followers engaging the inner ends of said wedges, and a pair of inner and outer helical release springs disposed in contact with the follower which engages the inner ends of the wedges at that end of the housing having the inclined surfaces disposed at the lesser angularity, the other ends of the outer helical springs engaging fixed portions of the housing, said fixed portions permitting the inner helical springs to pass therethrough and engage the other follower to maintain said follower in contact with the inner ends of the other wedges.

2. Cushioning mechanism adapted for use with railway draft rigging comprising a housing having an open end formed with inclined walls providing converging friction surfaces, wedges with

correspondingly inclined friction surfaces engaging the friction surfaces of the housing and movable thereinto, curved leaf springs disposed between said wedges for urging them apart and into engagement with the friction surfaces on the housing, an intermediate follower engaging the inner ends of said wedges, and springs engaging said follower for effecting release of the wedges, said wedges being provided with pockets adjacent the outer ends of the curved leaf springs and shoe castings formed with projections interlocking in said pockets and providing flanges overlying the ends of said springs and wedges to increase the bearing area with respect to an associated follower and retain the springs in proper position.

3. Cushioning mechanism adapted for use with railway draft rigging comprising a housing open at one end, said open end having opposite walls formed with inwardly converging friction surfaces, wedges having correspondingly inclined friction surfaces engaging the friction surfaces of the housing and movable thereinto, curved leaf springs disposed between said wedges for urging them apart and into engagement with the friction surfaces on the housing, an intermediate follower engaging the inner ends of said wedges, and release springs engaging said follower for holding it in contact with said wedges, the outer ends of said wedges being formed with pockets having outwardly flaring sides and shoes with wedge shaped projections fitting said pockets and interlocked with the wedges, the outer ends of said shoes having flanges overlying the ends of the curved plate springs for holding them in proper position and providing increased area for engagement with an associated follower.

4. Cushioning mechanism comprising a housing slotted adjacent the center thereof for receiving a connecting draft key, the ends of said housing flaring outwardly to provide inclined friction surfaces, the angularity between the friction surfaces at one end being greater than that at the other end, friction elements received in each end of said housing and presenting correspondingly inclined friction surfaces for engagement with the friction surfaces on the housing, resilient means disposed between said elements for urging them into engagement with the friction surfaces on the housing, and release springs for said friction elements, some of said springs serving for the elements at both ends of the housing and others acting on the elements at only one end thereof.

5. Cushioning mechanism comprising a housing slotted adjacent the center thereof for receiving a connecting draft key, a transverse partition adjacent said slotted portion dividing said housing into two parts, the ends of said housing flaring outwardly to provide inclined friction surfaces, friction elements received in each end of said housing and presenting correspondingly inclined friction surfaces for engagement with the friction surfaces of the housing, intermediate followers engaging the inner ends of said friction elements, and release springs disposed between said intermediate followers and the partition.

6. In railway draft rigging in combination with draft sills, a coupler and yoke acting means, a friction draft gear comprising a housing open at both ends and formed with inclined friction surfaces, friction elements with correspondingly inclined friction surfaces cooperating with said housing at each end, the inclination of the friction surfaces at the front or coupler engaging end being greater than that at the other end, said yoke acting means embracing said housing and friction

- elements for actuating the rear elements on draft, and a key received in a slot in said housing and slots in said sills, said sill slots being elongated rearwardly to permit rearward movement of the 5 housing on buff while holding it stationary on draft whereby the friction elements at both ends are operated on buff but only those at the rear end are operated on draft, said friction elements at the rear end having release springs comprising 10 inner and outer coils, the inner coils of said release springs being continued to act on the friction elements at the other end of the housing.
7. Cushioning mechanism adapted for use with railway draft rigging comprising a housing open 15 at each end, walls at said open ends formed with inwardly converging friction surfaces, the friction surfaces at one end converging at a sharper angle than those at the other end, friction elements having correspondingly inclined friction 20 surfaces engaging the friction surfaces of the housing and movable thereinto, resilient means disposed between said wedge means for urging them apart and into engagement with the friction surfaces on the housing, intermediate followers 25 engaging the inner ends of said wedges, and a plurality of release springs, all of said springs acting on one of said intermediate followers and only some of said springs acting on the other intermediate followers.
8. Cushioning mechanism adapted for use with railway draft rigging comprising a housing open 30 at one end and formed at said open end with converging walls providing friction surfaces, wedges with correspondingly inclined friction surfaces 35 engaging the friction surfaces of the housing and movable thereinto, resilient means disposed between said wedges for urging them apart and into engagement with the friction surfaces on the housing, said wedges being provided with 40 pockets adjacent their outer ends, and shoe castings formed with portions fitting in said pockets, said shoe castings having flanges for increasing the bearing area in respect to an associated follower.
9. Cushioning mechanism adapted for use as 45 railway draft rigging comprising a housing having an open end formed with inwardly converging friction surfaces, wedges having correspondingly inclined friction surfaces engaging the friction surfaces of the housing and movable thereinto, resilient means disposed between said 50 wedges for urging them apart and into engagement with the friction surfaces on the housing, the outer ends of said wedges being formed with pockets, and shoes with projections fitting said 55 pockets and interlocked with said wedges, the outer ends of said shoes having flanges for holding the resilient means in position and adapted to engage an associated follower for increasing 60 the effective frictional area.
10. Cushioning mechanism comprising a housing formed with a slot adjacent the center thereof for receiving means for connection with associated car sills, the ends of said housing having 65 flaring walls providing inclined friction surfaces, the angularity between the friction surfaces at one end being greater than that at the other end, friction wedges received in each end of the housing and having inclined friction surfaces in 70 engagement with the friction surfaces on the housing, resilient means disposed between said elements for urging them into engagement with the housing, and resilient means for effecting release of said elements, portions of said resilient means only acting on the elements at one end of 75

the housing and all of said resilient means acting on the elements at the other end.

11. Cushioning mechanism adapted for use with railway draft rigging comprising a housing having open ends formed with relatively fixed 5 inwardly converging friction faces, wedges with friction faces engaging the friction faces of the housing and movable thereinto, curved leaf springs disposed between said wedges to oppose movement thereof toward each other, said housing having a normally vertical partition uniting opposite walls, a normally horizontal partition forming a reinforcement uniting opposite walls of the housing, and merging into said vertical partition, said walls being provided with a slot 10 defined by upper and lower elements of said normally horizontal partition and adapted to receive a connecting draft key, release springs disposed on either side of said partitions, and an intermediate follower disposed between said springs and 20 the inner ends of said wedges.

12. Cushioning mechanism comprising a housing open at both ends, a set of friction elements and associated followers cooperating with said housing at each end, resilient means urging the 25 elements of each set into engagement with the housing, the engaging surfaces between said friction elements and housing converging inwardly and the inclination of the surfaces at one end being greater than that at the other, and the 30 inclinations being such, that the friction elements at one end are self-releasing while those of the other are not, and resilient means for effecting release of the friction elements having the friction surfaces of lesser inclination, a portion 35 of said resilient means being extended to hold the follower of the other friction elements in place.

13. Cushioning mechanism adapted for use with railway draft rigging comprising a housing 40 having an open end formed with relatively fixed inwardly converging friction surfaces, wedges with friction faces engaging said friction surfaces and movable into said housing, and resilient means disposed between said wedges to oppose 45 movement thereof toward each other, the inner ends of said wedges having lugs directed toward one another and the outer ends of said wedges having pockets and supplemental portions fitting in said pockets, said supplemental portions being 50 provided with lugs at their outer ends directed toward one another, all of said lugs being adapted to engage adjacent portions of said resilient means for preventing undesired movement thereof.

14. Cushioning mechanism comprising a housing with open ends and outwardly diverging walls adjacent said ends providing inclined friction surfaces, a transverse normally vertical partition dividing said housing into two compartments disposed one in front of the other, a normally horizontal partition, comprising vertically spaced webs connected at their ends, intersecting said vertical partition and dividing the compartments into upper and lower parts, a slot through said 65 housing, and defined, intermediate the side walls, by said webs of the normally horizontal partition, for receiving a connecting draft key, friction elements received in each compartment and presenting correspondingly inclined friction surfaces 70 for engagement with the friction surfaces of the housing, curved plate springs at each end of the housing disposed between and acting on the friction elements, intermediate followers engaging the inner ends of said friction elements, and 75

release springs disposed in the upper and lower parts of said compartments between said intermediate followers and partition.

15. Cushioning mechanism comprising a housing open at both ends and formed with inclined friction surfaces at each end, friction elements with correspondingly inclined friction surfaces and associated followers cooperating with said housing at each end, the inclination of the friction surfaces at one end being greater than that at the other end, so that the friction elements at said end, with friction surfaces of greater inclination, are self-releasing, while those at the other end are not, and resilient means for effecting release of the elements which are not self-releasing, a portion of said resilient means acting on the follower for the self-releasing elements.

16. Cushioning mechanism comprising a housing slotted adjacent its center for receiving a connecting draft key, a transverse web portion adjacent said slotted portion and serving to divide said housing into two parts, the ends of said housing flaring outwardly to provide inclined friction surfaces, friction elements received

in each end of said housing and presenting correspondingly inclined friction surfaces for engagement with the friction surfaces of the housing, an intermediate follower engaging the friction elements at one end of said housing, and a release spring disposed between said intermediate follower and said transverse web portion. 5

17. Cushioning mechanism comprising an outer friction member with normally upright side wall portions formed with receptacles to accommodate a connecting draft key, said member having another pair of walls comprising portions converging inwardly from both ends toward a central part and providing interior inclined friction surfaces, friction elements positioned between the converging portions of said walls and formed with correspondingly inclined friction surfaces directly engaging said interior inclined friction surfaces, followers engaging the inner ends of said friction elements, and springs acting longitudinally and engaging said followers for holding them in place and assisting in the release of the mechanism.

DONALD S. BARROWS.
